MEANS FOR SUPPORTING A BOW OR THE LIKE
William Goertzen, P.O. Box 27, Wasco, Calif.
Filed Aug. 30, 1961, Ser. No. 135,014
1 Claim. (Cl. 224—1)

This invention relates to means for supporting sporting equipment, and more particularly, to a device adapted to fully support a bow adjacent a sportsman's body.

Various devices have heretofore been suggested for use in supporting sporting equipment. Some of such devices take the form of a sling, other of such devices take the form of a pocket or the like, and still other of such devices take the form of a shelf-type rest. Although the particular devices and means previously suggested may function to advantage under certain conditions, there remains a need for an efficient and inexpensive device adapted to support an archer's bow adjacent the body of the archer, and accordingly the present invention has as its primary object the provision of a device which will satisfy such need.

Still a further primary object of the present invention is to provide a bow holder which is so designed that it can be fabricated by molded plastic techniques, and in addition, which is so designed as to fully support a bow whereby both of the sportsman's hands are free for desired use.

An additional, even further, and important object of the present invention is to provide a bow holder conforming with the preceding objects and having the support components thereof so arranged that a sportsman can with one hand readily and easily grasp the handle section of the bow and remove the same from the holder.

Yet other, still further, but more specific objects of the present invention are: (a) to provide a bow holder conforming with all of the preceding objects which is adapted to be fastened to a sportsman's belt and conform to the contour of his hip or waist so as to be comfortable in use; (b) to provide such a bow holder which, although preferably fabricated from plastic, can be fabricated from any suitable material inexpensively; (c) to provide such a bow holder which comprises a rear plate-like portion and spaced apart arms joined at their base to the plate-like portion and extending in spaced relation adjacent the face of the plate-like portion whereby a bow is supportable between the arms and the plate-like portion; (d) to provide such a bow holder wherein the arms are spaced apart by at least the width of the user's hand, and wherein the plate-like portion is provided with a recess aligned with the space between the arms so that the user's hand can be placed between the arms and within the recess to readily grip the handle section of a bow and remove it from the holder; (e) to provide such a bow holder wherein the arms serve in effect as spring-type gripping means adapted to press against and maintain the bow releasably fixed within the holder; and (f) to provide such a bow holder wherein the spacing between the respective arms and the face of the plate-like portion to which they are coupled is adjusted so as to accommodate thinner and thicker or wider and narrower portions of the handle section of a bow.

The invention lies in the construction and arrangement of the various members, portions, sections, and parts of the holder provided hereby, and will be better understood after consideration is given to the following detailed description. Such description refers to the preferred and illustrative embodiment of the invention presented in the annexed drawings, wherein:

FIGURE 1 is a side elevational view of the bow holder provided hereby, and presents the same as it would appear when supported on a sportsman's belt;

2

FIGURE 2 is a sectional view taken on the line 2—2 of FIGURE 1 and presents the arrangement and disposition of one of the arms of the holder with respect to the rear portion thereof;

5 FIGURE 3 is a section view taken on the line 3—3 of FIGURE 1 and presents the disposition and arrangement of the other arm of the bow holder with respect to the rear portion thereof; and

10 FIGURE 4 is a top end view of the holder shown in FIGURE 1, FIGURE 4 presenting most clearly the arched construction of the rear portion of the holder adapting the same to conform to the waist or hip contour of the user.

15 The holder, which is generally designated in the drawings by the numeral 2, preferably comprises an integral body including a rear portion 4 and a pair of arms 6 and 8 curved rearwardly at the base thereof and joining with the base of the rear portion 4. The rear portion 4 is arched transversely of the vertical axis thereof to conform to the waist or hip contour of the sportsman. The vertical axis is shown in phantom and designated as A in FIGURE 1, as well as in FIGURE 4. However, FIGURE 4 best presents the arched contour of such portion. The arms 6 and 8, as best shown in FIGURES 2 and 3, 20 extend in spaced relation to the front face 10 of the rear portion 4, and the respective arms 6 and 8 are laterally spaced apart by a distance D at least substantially as great as the width of a user's hand. The rear portion 4 has a recess or open section 12 between the end sections thereof, and by virtue of this open section, and the spacing between the respective arms 6 and 8, a user's hand can be readily placed on the handle section of a bow disposed within the holder.

25 Of course, the open section or recess 12 terminates in spaced relation to the top edge 14 of the rear section 4. As shown, the recess or open section 12 is preferably of inverted U-shape so as to facilitate fabrication, and in addition present an attractive appearance.

30 The rear portion 4 of the holder 2 is provided with means for coupling the holder to a sportsman's garment. As best shown in FIGURE 1, slots 18 and 20 are provided in the rear portion in the upper corner thereof whereby the sportsman's belt, generally designated by the numeral 22 can be passed through the respective slots in 35 conventional manner so that the holder is supported on such belt.

40 As suggested above, the holder 2 is preferably formed as an integral body from a suitable plastic material, such as, for example, polystyrene, or suitably adapted 45 polyethylene. Notwithstanding the fact that plastic construction is preferred, and constitutes an important aspect of the present invention, it will be readily apparent to those of ordinary skill in the art that the holder provided hereby can be formed from other suitable materials without departing from the scope and spirit of the invention.

45 In FIGURE 1, the handle section of a bow disposed within the holder is shown in phantom. The bow is generally designated by the letter B and the handle section thereof is generally designated by the letter H. In accordance with conventional construction, the handle section H includes as shown, a left portion which is narrower than the right portion. In other words, the handle section H includes portions of differing thicknesses or 50 widths.

55 To accommodate and positively grip the handle section of such a conventionally constructed bow, the spacing between the arm 6 and the front face 10 of the rear portion 4 is less than the spacing between the arm 8 and the front face 10 of the rear portion 4. In FIGURE 60 2, the left portion of the handle section H is designated 65

by the letter H' and is shown in phantom as disposed within the holder and gripped between the arm 6 and the rear portion 4. In FIGURE 3, the right portion of the handle section H is shown in phantom and designated by the letter H''. Portion H'' is substantially thicker than portion H' and the arm 8 is thus spaced further from the front face 10 of the rear portion 4 of the holder so as to accommodate the portion H'' as shown.

While the differential spacing between the respective arms and the rear portion 4 is provided in a holder constructed in accordance with the preferred embodiment of the invention, it should be understood that the holder can, in certain instances, be constructed without providing for such differential spacing, i.e. in instances where the handle section H has portions of uniform thickness, or substantially uniform thickness, to be gripped by the respective arms 6 and 8.

The base portions 6' and 8' of the respective arms 6 and 8 preferably have a generally semi-circular contour adapted to generally conform with the contour of the handle portions disposed thereadjacent when the bow is carried within the holder. Moreover, the arms 6 and 8 preferably have outwardly flared upper ends 6'' and 8'' respectively. The outward flaring of the upper ends not only permits ready removal of a bow disposed within the holder, but in addition serves to provide a guide when a user desires to place a bow within the holder.

To rephrase the terminology, the holder, which is generally designated in the drawings by the numeral 2, preferably comprises an integral U-shaped plate member arched transversely of the vertical axis thereof comprising an upper portion 30 having slots 18 and 20 and a contiguous lower portion 31. The lower portion 31 comprises a pair of spring arms 6 and 8, curved forwardly to form U-shaped arms. U-shaped arm 6 comprises a forward leg 32 and a rear leg 33 and a bight 34 connecting said legs. U-shaped arm 8 comprises forward leg 35, a rear leg 36 and a bight 37 connecting said legs. The forward legs 32 and 35 of the U-shaped arms 6 and 8, as best shown in FIGURES 2 and 3, extend in spaced relation to the rear legs 33 and 36, respectively, and the bight 34 of the arm 6 is of a smaller dimension than the corresponding bight 37 of arm 8 so as to generally conform with the contour of the bow handle. The bights 34 and 37 of U-shaped arms 6 and 8 are so located on the respective U-shaped arms 6 and 8 that the forward legs 32 and 35 of the U-shaped arms extend in an upward direction and in spaced relation to a point at least parallel to the slots 18 and 20 contained in the upper portion 30 of the holder 2.

Although, as suggested above, the holder 2 may be formed from any suitable material, and preferably from a plastic, it is to be understood that the material should inherently be sufficiently elastic to permit some outward bending of the arms 6 and 8 with respect to the rear portion 4 during insertion of a bow within the holder and so as to also provide for at least limited spring-type gripping of the bow, or handle section thereof, by the arms.

After reading the foregoing detailed description, it should be apparent that the objects set forth at the outset of this specification have been successfully achieved, and that the invention provides a bow holder adapted to support a bow adjacent a sportsman's body whereby both

of the sportsman's hands are free for use. It should also be apparent that such holder can be easily and inexpensively manufactured, and that various modifications can be made thereto, other than those suggested specifically hereinabove, without departing from the scope and spirit of the invention. Accordingly, what is claimed is:

- A bow holder adapted to support a bow adjacent a sportsman's body whereby both of the sportsman's hands are free for use, said bow holder comprising:
- (a) an integral U-shaped plate member fabricated of resilient plastic;
  - (b) said plate member having a continuous upper portion arched transversely of the vertical axis thereof to conform to the waist contour of a sportsman;
  - (c) a pair of U-shaped arms disposed at opposite ends of said upper portion and depending therefrom to define the lower portion of said plate member;
  - (d) each of said U-shaped arms being formed of an inner leg, an outer leg spaced therefrom and a bight portion connecting said inner and outer legs together;
  - (e) said inner legs being integrally affixed to said upper portion and said outer legs thus being spaced outwardly of said upper portion;
  - (f) said upper portion having spaced slots therein for coupling said bow holder to a belt disposed in surrounding relation to the sportsman's waist;
  - (g) said upper portion having a lateral extent sufficient that said U-shaped arms at the ends thereof are spaced apart by a distance at least substantially as great as the width of a sportsman's hand whereby said sportsman can facilely introduce and remove a bow from said holder while it is being worn in coupled relation to his belt;
  - (h) said outer legs being spaced from said inner legs by said bight portions to form bow receiving recesses at the base of said U-shaped arms;
  - (i) one of said bight portions having a length greater than the other of said bight portions whereby one of said recesses has a spacing which is greater in width than the other of said recesses to thus permit said bow to be accommodated with its portions of various thicknesses being properly received within the correspondingly sized recesses;
  - (j) said outer legs extending upward from said bight portions to a height at which the terminal ends thereon are disposed oppositely of said slots; and
  - (k) said outer legs curving inwardly above said bight portions and then curving outwardly at their terminal ends to permit said bow to be readily introduced into said holder and to be snugly retained therein due to the resiliency of the plastic of said arms which causes the inwardly curved portions of said outer legs to extend over said bow as said bow is resting within the recesses in said holder.
